UNITED STATES PATENT OFFICE.

WILLIAM ARTHUR GRIFFITHS, OF HOMESTEAD, PENNSYLVANIA.

GARMENT-HANGER.

1,184,743.

Specification of Letters Patent. Patented May 30, 1916.

Application filed April 9, 1915. Serial No. 20,127.

To all whom it may concern:

Be it known that I, WILLIAM ARTHUR GRIFFITHS, a citizen of the United States, residing at Homestead, in the county of Allegheny and State of Pennsylvania, have invented certain new and useful Improvements in Garment-Hangers, of which the following is a specification.

This invention relates to garment hangers and has for its object to provide a device of such class, in a manner as hereinafter set forth, which can be folded in an unusual compact manner when not in use and to further provide a hanger formed of a series of sections and having means in a manner as hereinafter set forth, for rigidly maintaining the sections in position when extended and when folded.

Further objects of the invention are to provide a garment hanger which is simple in its construction and arrangement, strong, durable, efficient and convenient in its use, readily set up and comparatively inexpensive to manufacture.

With the foregoing and other objects in view the invention consists of the novel construction, combination and arrangement of parts as hereinafter more specifically described and illustrated in the accompanying drawings, wherein is shown an embodiment of the invention, but it is to be understood that changes, variations and modifications can be resorted to which come within the scope of the claims hereunto appended.

In the drawings wherein like reference characters denote corresponding parts throughout the several views:—Figure 1 is a front elevation of a garment hanger in accordance with this invention, the hanger being extended. Fig. 2 is a top plan view of a hanger when extended. Fig. 3 is a top plan view of a hanger when folded.

Referring to the drawings in detail the hanger consists of a body portion 1, having hinged thereto a pair of foldable sections or members 2, 3. The body portion 1 is arcuate and the members 2, 3, segmental in contour whereby when the members 2, 3, are extended with respect to the body portion 1 an arcuate support or hanger will be provided for the garment.

The member 2 is hinged to the member 1, as at 4, and the member 3 hinged to the member 1 as at 5. The hinge connection between the member 2 and the body portion 1 is on the opposite side of the body por-

tion 1 with respect to that side on which is arranged a hinge connection 5 for the member 3 and by such an arrangement the members 2, 3, are folded to extend parallel with respect to opposite sides of the body portion 1. The body portion 1 at the top thereof is formed with a lengthwise extending recess 6 which starts from one end of said body portion and terminates beyond the center thereof and the bottom wall of said recess gradually inclines downward toward the inner end of the recess, as at 7. Extending across the recess 7, at the inner end thereof, is a pin 8, and pivoted upon said pin 8 is the looped end 9 of the hook 10. The hook 10 when shifted to the position shown in Fig. 1 is employed for suspending the body portion 1. Each side of the body portion 1 has a seat, said seats being indicated at 11 and 11^a, and the said seats are out of alinement, and each side of the body portion 1 has pivotally connected therewith a hook, said hooks are indicated at 12 and 12^a, and one of said hooks projects from one end of the body portion and the other of said hooks projects from the other end of the body portion. The member 2 is provided on opposite sides with lateral projecting eyes 13, 14, the former arranged in proximity to the outer end of the member and the latter in proximity to the inner end of the member. The member 3 is provided on lateral projecting sides with lateral projecting eyes 15, 16, the former is positioned in proximity to the inner end of the member 3 and the latter in proximity to the outer end thereof. When the members 2, 3, are extended with respect to the body portion 1, the hook 12^a engages in the eye 14 and the hook 12 engages in the eye 15 under such conditions the members 2, 3, are maintained in extended position.

When the members 2, 3, are folded so as to extend in parallelism with the sides of the body portion 1, the eye 16 extends in the seat 11^a and the eye 13 extends in the seat 11. The hook 12^a engages in the eye 16 and the hook 12 engages in the eye 13 whereby the members 2, 3, are maintained in a folded position with respect to the body portion 1. When the members 2, 3, are folded the hook 10 is shifted down into the recess 6.

What I claim is:—

A garment hanger comprising an arcuate body portion, a suspension hook carried

thereby, a pair of oppositely foldable and curvey members capable of being positioned parallel with opposite sides of the body portion, means carried at each side at opposite ends of said body portion for hinging said members therewith, a laterally projecting eye secured to each side at opposite ends of each member, a pivoted hook carried by each side at opposite ends of said body portion and when swung outwardly engaging in the eyes at the inner ends of said members to maintain these latter extended to provide a continuation of the body portion and when swung inwardly engaging in the

eyes at the outer ends of said members to 15 maintain these latter in parallelism with each other and with the body portion said body portion having each side near the pivot of a hook provided with a seat to receive the eyes at the outer end of the members 20 when these latter are secured by the hooks in parallelism.

In testimony whereof I affix my signature in presence of two witnesses.

WILLIAM ARTHUR GRIFFITHS.
